(57) **CLAIM**

The ornamental design for a hitch for a truck front end, as shown and described.

DESCRIPTION

FIG. 1 is a perspective view of the hitch for truck front end of the present invention which is adapted for use on the front end of a tow vehicle, such as a pickup truck.

FIG. 2 is a front elevation view of the hitch for truck front end of the present invention.

FIG. 3 is a rear elevation view of the hitch for truck front end of the present invention.

FIG. 4 is a right side elevation view of the hitch for truck front end of the present invention.

FIG. 5 is a left side elevation view of the hitch for truck front end of the present invention.

FIG. 6 is a top plane view of the hitch for truck front end.

FIG. 7 is a bottom plane view of the hitch for truck front end; and,

FIG. 8 is a perspective view showing the front hitch for truck front end mounted on the front end of a pickup truck with a trailer attached thereto, though the truck and trailer form no part of the present invention.

Structure, environment, and/or boundaries shown in broken lines form(s) no part of the claimed design.
